EDWARD SEALY, OF NEWARK, NEW JERSEY.

Design No. 2,829, dated November 5, 1867.

DESIGN FOR A PENDANT FOR HAT-BAND.

The Schedule referred to in these Letters Patent and making part of the same.

TO ALL WHOM IT MAY CONCERN:

Be it known that I, EDWARD SEALY, of Newark, in the county of Essex, and State of New Jersey, have invented or produced a new and original shape or configuration of the article of manufacture known as a Pendant for a Hat-Band; and that the following, taken in connection with the accompanying drawing, is a description of the same.

The novel shape or configuration of pendant for a hat-band which I have produced, as represented in the accompanying drawing, is a perforated lozenge-shaped plate of thin metal, *a*, connected by a link, *b*, with a drop, *c*. I prefer to make the lozenge-shaped figure *a* of a length about as great as the width of the hat-band to the end of which it is secured.

The perforations of the figure afford a convenient means of securing the pendant by screwing it, and the article is a neat and handsome finish to a hat-band for boys' hats.

I claim the design, as described and represented, as a pendant for a hat-band.

In testimony whereof I have hereto set my hand this third day of August, 1867.

EDWARD SEALY.
